UNITED STATES PATENT OFFICE.

EDWIN EARL Vining, of Utica, Kansas, assignor of one-half to LOY MUCHMORE, of Utica, Kansas.

CLOTHESPIN.

Application filed March 9, 1923. Serial No. 623,993.

To all whom it may concern:

Be it known that I, EDWIN EARL Vining, a citizen of the United States, residing at Utica, in the county of Ness and State of Kansas, have invented a new and useful Clothespin, of which the following is a specification.

This invention aims to provide a clothes pin which, considering its construction, can be manufactured cheaply out of wire or like material, the pin having an unusually secure hold, and being so constructed that it may be locked in gripping position and be unlocked from gripping position without difficulty.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in elevation, a pin constructed in accordance with the invention; Figure 2 is an elevation wherein the pin is viewed at right angles to the showing of Figure 1; Figure 3 is an elevation wherein the opposite side of the pin appears from that which is disclosed in Figure 1; Figure 4 is an end elevation of the pin.

The clothes pin forming the subject matter of this application comprises a U-shaped main lever 1 including side arms 2 bent upon themselves to form bearings 3, the side arms being continued beyond the bearings to fashion loop-shaped jaws 4 which are bent to define internal seats 5, the jaws having free ends 6 disposed inwardly of the outer side portions of the jaws. The side arms 2 of the main lever 1 are connected by a support 8, in the form of a rod.

The clothes pin embodies a U-shaped auxiliary lever 9 which is of less width than the main lever 1, the lever 9 embodying side arms 10 bent upon themselves to form bearings 11, the side arms being continued to form loop-shaped jaws 12, the free ends 14

of which are disposed outwardly of the inner side portions 15 of the jaws. A keeper 16 is connected at its ends to the side arms of the lever 9 and is provided in its lower edge with a notch 17.

The levers 1 and 9 are crossed with respect to each other, the bearings 3 and 11 being alined to receive a pivot element 18 constituting a fulcrum for the levers, the bearings 3 of the lever 1 being disposed outwardly of the bearings 11 of the lever 9, the free ends 14 of the jaws 12 being disposed close to the outer side portions 7 of the jaws 4, and the free ends 6 of the jaws 4 being disposed close to the inner side portions 15 of the jaws 12. The jaws 12 cooperate with the seats 5 of the jaws 4 to grip the article which is to be held on the clothes line.

The pin includes a U-shaped latch 19 comprising a long arm 20 and a short arm 21, the arms of the latch being mounted on the support 8 which connects the side arms 2 of the lever 1, the latch thus being mounted for swinging movement on the support 8. A helical spring 22 is located between the long arm 20 and the short arm 21 of the latch 19 and surrounds a portion of the support 8. One end 23 of the spring 22 is engaged with one arm 2 of the lever 1, and the other end 24 of the spring 22 is engaged with the long arm 20 of the latch 19, the spring 22 thus tending to swing the long arm 20 of the latch 19 into engagement with the keeper 16 which connects the side members 10 of the auxiliary lever 9, the part 20 of the latch 19 having teeth 25 adapted to engage the keeper. The ends of a loop-shaped guard 26 are engaged with the part 20 of the latch 19, the guard 26 passing about the keeper 16. A helical spring 27 is located between one of the bearings 3 of the lever 1 and the adjacent bearing 11 of the lever 9 and is disposed about a portion of the pivot element 18, one end 28 of the spring 27 being engaged with one side arm 10 of the lever 9, and the other end 29 of the spring 27 being engaged with one arm 2 of the lever 1 the tendency of the spring 27 being to swing the jaws 12 and 4 apart.

In practical operation, when the upper ends of the levers 1 and 9 are pinched together, the jaws 4 and 12 grip the garment on the line, the arm 20 of the latch 19 riding along the upper edge of the keeper 16, and

the teeth 25 of the latch engaging automatically with the keeper, under the impulse of the spring 22. The jaws 4 and 12, thus, are locked in engagement with the garment on the clothes line.

In order to release the pin, the latch 19 is swung upwardly at the end marked by the numeral 30 in Figure 2, the guard 26 being received in the notch 17 of the keeper 16 and limiting the upward movement of the arm 20 of the latch and when the arm 20 of the latch is raised, the teeth 25 are disengaged from the keeper 16 whereupon the jaws 4 and 12 swing apart, responsive to the spring 27.

What is claimed is:—

1. A clothes pin comprising crossed levers having cooperating jaws, a keeper carried by one lever, a latch pivoted on the other lever and cooperating with the keeper to hold the jaws against separation, and spring means for moving the levers to separate the jaws when the latch is disengaged from the keeper.
2. A clothes pin comprising crossed levers provided with coacting jaws, a keeper carried by one lever, a latch pivotally mounted on the other lever and cooperating with the keeper, and a loop-shaped guard carried by the latch and extended about the keeper to limit the movement of the latch when the latch is swung away from the keeper.

3. A clothes pin comprising pivotally connected levers having cooperating jaws, spring means operating upon the levers to separate the jaws, a keeper carried by one lever, a latch mounted pivotally on the other lever and coacting with the keeper to hold the jaws against separation, spring means for maintaining the latch engaged with the keeper, and a loop-shaped guard carried by the latch and extended about the keeper to limit the movement of the latch when the latch is swung away from the keeper.

4. A device of the class described, constructed as set forth in claim 4 and further characterized by the provision of spring means cooperating with the levers to separate the jaws, the latch coacting with the keeper to hold the jaws against separation, spring means for maintaining the latch releasably engaged with the keeper, and a guard carried by the latch and cooperating with the keeper to limit the swinging movement of the latch when the latch is swung away from the keeper.

In testimony that I claim the foregoing as my own, I have hereto affixed by signature in the presence of two witnesses.

EDWIN EARL VINING.
